Primary Examiner — W. A. Teddy Falloway*Assistant Examiner* — Amanda Kay Birdwell(74) *Attorney, Agent, or Firm* — Olive Law Group, PLLC(57) **CLAIM**

The ornamental design for a packing box, as shown and described.

DESCRIPTION

FIG. 1 is a bottom, front and right side perspective view of a packing box showing my new design; FIG. 2 is a top, front and right side perspective view thereof; FIG. 3 is a bottom plan view thereof; FIG. 4 is a top plan view thereof;

FIG. 5 is a left side elevational view thereof;

FIG. 6 is a right side elevational view thereof;

FIG. 7 is a front elevational view thereof;

FIG. 8 is a rear elevational view thereof; and,

FIG. 9 is a plan view of the packing box in an unassembled configuration.

The broken lines shown in FIG. 9 represent fold lines that form part of the claimed design.
